UNITED STATES PATENT OFFICE

WILLIAM W. MACFARLANE, OF ELKINS PARK, PENNSYLVANIA, ASSIGNOR, BY MESNE ASSIGNMENTS, TO THE UNION SWITCH & SIGNAL COMPANY, OF SWISSVALE, PENNSYLVANIA, A CORPORATION OF PENNSYLVANIA

TRAIN-CONTROL SYSTEM

Application filed October 19, 1914, Serial No. 281,552. Renewed March 8, 1919.

The present invention relates generally to traffic controlling devices, and has more particularly reference to train controlling systems.

In the art, as heretofore practiced, an indication of traffic conditions has usually been given to a train at definite intervals or intermittently—say at the beginning of each block. The main object and feature of this invention is to give a continuous indication of the traffic conditions of the rails, within a certain zone of the train, to the train as it passes over the line of way.

For this purpose a translating device is used on the train which is continuously responsive to and energized by the current flowing through the rails or through one rail and a conductor other than a rail in such a manner that a signal may be given or the train may be otherwise controlled at any point in the block through which it is traveling. The advantage of this is that no matter how often traffic conditions may change, within a given zone of the train, such change will immediately be indicated to the approaching train, either by the giving of signals or by controlling the speed of the train, or by both. The train therefore does not have to wait until it reaches the end of the block before the traffic conditions of other blocks can be ascertained. In this manner traffic can be handled with greater safety and with less delay than with an intermittent system of traffic control.

In the accompanying drawings and specification the invention is embodied in a concrete and preferred form, from which changes may be made without departing from the intended and legitimate scope of the invention as expressed in the appended claims.

Figure 1 is a general diagrammatic view of a system embodying the invention.

Figure 2 is a plan detail view of one of the contact shoes and adjacent parts used to pick up the track current.

Figure 3 is a sectional view on the line 3—3 of Figure 2.

Figure 4 is a side elevation of the parts shown in Figure 2.

Figure 5 is a sectional view on the line

5—5 of Figure 6 of the translating device in the main traffic control circuit.

Figure 6 is a sectional view on the line 6—6 of Figure 5.

Figure 7 is a side elevation of one of the speed controlling devices.

Figure 8 is a side elevation of the speed controlling device shown in Figure 7 with the cover removed.

Figure 9 is a transverse sectional view on the line 9—9 of Figure 8.

Figure 10 is a vertical sectional view through one of the mercury bulbs and the wires leading thereto.

Figure 11 is a detail view of one of the means for operating the speed controlling device.

Similar characters of reference indicate corresponding parts in the several views.

1 indicates a translating device, on the car 70 2, which is continuously responsive to the current flowing through the rails 3 and 4 in this instance of the traffic track.

This translating device is in its present embodiment responsive both to variations in the characteristic of the current flowing through the rails as well as to the absence of such current. The variations in the current may be produced in various ways, such as by changing the phase or the frequency of an alternating current, or, as in the present form of the invention, by changing the polarity of a direct current.

To effect this the translating device, in its present embodiment, partakes of the nature 85 of a polarized relay and is constructed as follows:

5 indicates a magnet having the poles 6 and 7 under the influence of which is a polarized armature 8 controlled by springs 9, which will, in the absence of current, hold the armature in its central position. The magnet 5 is located in or in itself constitutes a low resistance path on the car across from one rail to the other so that the track current will naturally take this path in preference to any other. As here shown, this low resistance path consists of shoes 10 of a suitable material, such as iron or copper or both, which shoes contact with the rails 3 and 4 100

and are carried by slots 11 in a stationary portion of the car 2 and mounted thereon by means of the pins 12, a spring 13 serving to maintain the contact shoes in engagement with the traffic track. Reaching across the car is a cylinder or other body of copper 14 which is electrically connected to the shoes by means of the copper cables 15. This cylinder or body of copper 14 is milled throughout a portion of its length, as shown at 16, with a spiral cut so as to produce a spring or helical-shaped body. This body 14 is further bored longitudinally as at 17 and is provided with a core 18 of soft iron insulated from the main body portion 14 by means of the insulating material 19. Each pole 6 and 7, also of soft iron, extends through the side of the body 14 into the core 18 where it is held in position by being in threaded engagement therewith, as shown, and is insulated from the main body portion 14 by means of the insulation bushings 20. This body 14 forms a low resistance path through which the track circuit will easily pass from one rail to the other.

Suitable traffic controlling means are controlled by this translating device, which means may be of any suitable character and consists either of signals or of speed controlling devices or both. For the present, however, it will only be necessary to consider what I shall term the main traffic control circuit of the train.

For the sake of convenience the poles 6 and 7 of the magnet 5 constitute the two terminals of one side of the main traffic control circuit which is fed by the battery 21, from which latter extends the conductor 22 which connects to the binding post 23 on the pole 7, which pole is in circuit with the other pole 6 through the core 18. The other side of the battery 21 is connected to the two terminals 24 and 25, the first one by means of conductor 26, relays 27, conductor 28, and the second one by means of conductor 29, magnets 30 and conductor 31.

It will be apparent that if a track current of a certain polarity flows through the low resistance path from one rail to the other, the poles 6 and 7 will be energized and the polarized armature 8 will move say to cause the terminal 24 to engage the combined pole and contact member 6. When this happens it will be under normal running conditions and current will flow from the battery 21, along conductor 28, coils 27, conductor 26, contact 24, pole piece 6, binding post 23, and conductor 22 back to battery.

If now current of the reverse polarity from that previously considered flows through the low resistance path the poles 6 and 7 will be energized in such a way that the armature 8 will move into position to cause the terminal 25 to engage the combined pole and contact member 7. Current now flows from battery

21, along conductor 31, coils 30, conductor 29, contact member 25, through pole 7, to binding post 23, along conductor 22 back to battery.

The magnets 27 and 30 together with the neutral armature 32 constitutes a translating device in the main traffic controlling circuit. For the purpose of illustration at this point it will be convenient to consider the effect of the currents of different polarity or of the absence of current upon this translating device only in so far as it effects simple signals.

The armature 32 is suspended by means of flat springs 33 from a suitable supporting member 34, which springs always tend to return the armature 32 to its central position.

Connected to the armature 32 through the medium of the supporting member 34 is a conductor 35 which is connected to one side of the battery 21 through the conductor 22. 36 indicates a conductor leading from the battery 21 which has parallel branches 37, 38 and 39 terminating in contacts 40, 41 and 42. In these parallel branches are located the signal lights W, G and R which respectively indicate white, green and red.

When the coils 27 are energized by current from the battery 21 the armature 32 will be drawn toward the said coils and will close a circuit as follows: from battery 21, through conductor 36, conductor 37, through the light thereof, contact 40, armature 32, conductor 35, through conductor 22, back to battery. So long as the armature 32 remains in its uppermost position this white signal will be given showing safe traffic conditions. If now the reversal of the polarity of the current through the low resistance path causes the energization of the coils 30, a circuit would be established as follows: from the battery 21, conductor 36, conductor 38 and the light thereof, contact 42, to armature 32, conductor 35, through conductor 22, back to battery 21. This will display a green light and will indicate that the train should proceed under caution. If now no current is flowing through the low resistance path no circuits will be closed and the armature 32 will remain in its mid-position thereby establishing a circuit as follows: from battery 21, conductor 36, conductor 39 and the light thereof, contact 41, armature 32, conductor 35, conductor 22, back to battery 21. This will display a red light which indicates a danger condition.

Having now observed the effect of currents of different polarity and of the absence of current upon the low resistance path and its translating device and the effect thereof upon the main traffic controlling circuit, I now proceed to describe the means whereby the characteristic of the current in the track may be varied or whereby current may be cut off altogether.

The rails 3 and 4 are divided by insulation 43 in a well-known manner so as to produce

blocks A, B, C, D and E of requisite length.

Each block is provided with a main track battery 44a, 44b, 44c, and 44d connected through the conductors 58, 57 and 61 to one track rail and through the conductors 45, 48, 50 and 52 to the other track rail. These batteries are arranged to provide the usual low voltage current to the track rail circuit but differ from the ordinary track batteries heretofore known in that they are arranged to furnish a current of comparatively large volume whereas the volume of current furnished by the usual track battery is comparatively small.

The track circuit is normally completed through conductors 55 and 53 leading from the track rails at the end of the block opposite the track battery to relays 54a, 54b, etc., as the case may be. The coil of each relay 54 is given such a resistance value that, combined with a low resistance element X, that is preferably included in the conductor 45, the current flowing through the track circuit when a train is not in the block will have very little tendency either to leak through the rail insulation or to exhaust the battery.

A small battery 63 preferably arranged to furnish both a low voltage and a small volume of current is also connected to the track rails through the conductors 68 and 64. Conductors 67, 66 and 65 lead from the rails at the opposite end of the block and include the relay coil 62. This battery cannot furnish any current that will have any effect on the train controlling device.

Normally when a train is not present in a block the battery 44 energizes the relay coil 54 of the block to the rear through the track circuit already traced. The armature 51 of the relay acts as a pole changer and in the energized condition of the relay coil the current flows through the track circuit in a direction to flow across from say rail 3 to rail 4 through the axles of a train which may enter the block. This situation is represented in Fig. 1 of the drawing which shows a train in block C with a safety signal displayed in the cab.

Considering now the effect that the train in block C has on the blocks B and A to the rear, it will be noted that relay coil 54b of block B is shortcircuited by the presence of the train in block C, the current flowing from battery 44c through conductors 58 and 57, armature 51, conductors 61 and 56, rail 3, low resistance path 5, rail 4, conductor 52, armature 51, conductors 50, 48 and 45 back to battery, instead of flowing through the conductor 55, the comparatively high resistance 54b, and the conductor 53. The effect of de-energizing relay 54b is to reverse the pole-changer 51 through which battery 44b is connected to the rails 3 and 4 of block B.

The presence of the train in block C also short circuits relay 62b which is controlled

from battery 63c already referred to. The effect of this is to open the circuit of block B which is normally completed through conductors 48 and 50 at the break 49. This interrupts the track circuit of block B and de-energizes the relay coil 54a of block A to reverse the flow of current through the rails of that block.

In addition to the connections of the batteries 44a, 44b, etc. to the rails of the block sections already referred to, these batteries are also connected to the rails of the blocks immediately in advance through the conductors 59 and 67 on the one hand, and conductors 45, magnet 69 and conductor 65 on the other, with this arrangement the battery 44b of block B energizes the magnet 69b, flowing across the axles of the train in block C to complete a circuit. The energization of magnet 69b opens the circuit through conductors 45 and 48 at the point 47, thus providing a second break in the track circuit of the block B.

It is to be noted that in block B the battery 63b is available to energize the relay 62a of block A thus closing the break 49 in the track circuit of block A. Also the battery 44a, since there is no train in block B, can no longer energize relay 69a so that the second break at 47 in the track circuit of block A is closed.

The magnet 69b is arranged to provide a relatively high resistance so that the current flowing through the train axles in circuit with the magnet 69 will have no effect on the controlling devices carried by the train. It is also to be noted that the two magnets 62 and 69 which are arranged in series in the circuits 59, 66, 45 and 44 are given such resistance values in relation to the battery 44 that they are unaffected by this battery.

Thus it will be seen that the track circuit of the block immediately in the rear of a train-occupied block is interrupted so that a train entering such block would fail to pick up current and would be stopped while the second block in the rear of a train-occupied block will have its track circuit reversed to display a caution signal in the cab of a train entering such block.

From the foregoing it will be observed that when a train is traveling through a block, current in a certain direction will pass through the low resistance path of the car and will maintain a continuous white light in the cab in the manner previously described. Should now another train approach within two blocks of the first train, it will encounter a reverse flow of current in the manner described and will consequently receive a green light until traffic conditions change. If a train should enter the block immediately behind one occupied by another car, no current flowing in said block immediately behind the other car, the red signal will be given in the

130

main traffic controlling circuit in the manner described.

While there is no current from the battery 44 present in the rails of the section immediately behind the one occupied by a car, it will be noted that current is still flowing in this section from the auxiliary battery 68 in order to maintain the contact 49 closed in the next succeeding block.

10 It is pointed out that the resistance of the magnet 54 is such, that in addition to preventing the energization of the magnets 62 and 69 by the battery 44, the energization of the magnet 69 and the magnet 54 of the block in advance through the circuit 45, 69, 65, 55, 53, 67, 59 is also prevented.

As has already been pointed out, the relay 54 together with the small resistance X have such a value in relation to the battery 44 that 20 a current of very small volume flows through the track circuit in a block when a train is not present. The shunting out of the comparatively high resistance relay 54 by the entrance of a train into a block under safety or caution 25 conditions immediately renders available a current sufficiently large in volume to insure the operation of the train-carried controlling device. At the same time the retention of the low resistance X in the circuit prevents 30 such an undue volume of current to flow as would injure the battery.

The shoes 10 are preferably located on the car between the pony trucks, and if desired the axles in advance of such shoes can be insulated between parallel rails so that no current can pass across from one rail to the other through said axles. The resistance of the body 14 is very low, say one-fifth of the resistance of the two wheels at the point of 40 contact with the rail and the axle connecting the same. Or to state it differently the resistance of the body 14 is about the same as the resistance of about fifteen feet of unbonded rail (100 lbs.). It may therefore not 45 be necessary to provide insulation between the opposite wheels.

100 indicates the train line controlled by the valve 101 which when opened will cause a sufficient reduction in the train line to give 50 a service application of the brakes. The stem 102 of the valve body proper is shown as projecting above the casing of the valve and the said valve will be opened when the lever 103 pivoted at 104 is depressed by means of a 55 bifurcated arm 105 pivoted at 106 and having an abutment member 107. A spring, not shown, inside the valve will normally tend to raise the valve stem 102 into its uppermost position. 108 indicates an actuating member 60 mounted on the shaft 109 and normally held out of engagement with the abutment member 107 by means of the coiled spring 110 which presses said actuating member 108 home against the stop 111. Mounted to move 65 with this actuating member 108 is a ratchet

112 adapted under certain conditions to be actuated by the pawl 113 mounted on the eccentric 114 and having an extension 115 forming an armature for the magnet 116. 117 indicates a back pawl pivoted at 118 and having 70 also an extension 119 which forms an armature for the magnet 120. The pawl 117 also carries a circuit closer 121 which controls a circuit to be presently described, for energizing the magnet 116. The eccentric 114 is continuously driven by suitable transmission from the axle 122 of the car such as the gears 123 and flexible shaft 124. The flexible shaft 124 is connected fast to the casing 125, which casing carries a pawl 126 that engages with a ratchet 127 fast on the shaft 128 on which the eccentric 114 is mounted. The pawl 129 is a stop pawl to prevent the ratchet from reversing.

It will be observed that the pawl 113 is constantly actuated so long as the train is moving but is normally prevented from engaging the ratchet 112 by reason of its extension 115 which remains in sliding contact with the magnet 116. Similarly the back pawl 117 is 20 normally out of engagement with the ratchet 112. When, however, these two magnets 116 and 120 become deenergized the pawl 113 drops by gravity into engagement with the teeth of the ratchet 112, as does the pawl 117, 25 and the rotation of the shaft 128 and the eccentric 114 will therefore feed the ratchet wheel 112 forward intermittently in one direction acting against the opposition of the spring 110. The ratchet 112 will carry the 30 actuating member 108 with it until it engages the abutment member 107 and opens the valve 101.

Driven from the shaft 128 is a speed governing device in the form of a rotatable bulb 105 of a fragile material as glass, containing mercury and forming in connection with the requisite conductors a circuit closer and opener. As here shown the shaft 128 carries a large bevel gear 130 which engages with a bevel pinion 131 carried by the hollow shaft 132 and its connecting wires. The mercury bulb 133 may be variously shaped, its shape depending upon the amount of displacement of the mercury desired at certain speeds of 110 rotation. Dipping into the mercury contained in the bulb 133 are conductors, as shown more particularly in Figure 10, which pass up through the interior of the shaft 132, being suitably insulated from each other as 115 shown.

When traffic conditions are safe and a white light is showing in the cab, the armature 32, as previously described, will be attracted by the relays 27. In these circumstances a circuit as follows is established through the coil of the magnet 120: from battery 21, to wire 134, conductor 200, to binding post 81 and thence to coil 120, by means of conductor 135, thence by conductor 136, to 125

binding post 80, thence by conductor 137 and conductor 138 to contact 139, armature 32, conductor 35, conductor 22, battery 21, if now a green light is displayed in the cab and the armature 32 is attracted by the coils 30, then a circuit as follows will be established: from battery 21, along wire 134, conductor 200, to binding post 81, to coil 120, to binding post 80, conductor 137, conductor 140 to contact 141, mercury 142, contact 143, conductor 144, conductor 145, conductor 146, contact 147, armature 32, conductor 35, conductor 22, back to battery 21. This circuit, however, could only be established when the train is running at a given speed, say five miles an hour, since if this or some other predetermined speed is exceeded the mercury will have been displaced with respect to the contacts 141 and 143 and the circuit will be broken, and in that event the magnet 120 will become deenergized and its pawl 117 will drop into engagement with the ratchet 112 and its circuit closer 121 will be moved out of contact with the points 147 and 148, thereby destroying the following circuit through the magnet 116: from binding post 81, by way of conductor 149 through coil 116, through conductor 150, contact 147, circuit closer 121, contact 148, conductor 151 to binding post 80. The rupturing of this circuit and the deenergization of the magnet 116 will cause the pawl 113 to engage with the ratchet 112 and thus cause a reduction in the train line by the means previously described.

If a red signal is given in the cab then the armature 32 will be in the middle position and the following circuit will then be established: battery 21, along conductor 134, conductor 200, to binding post 81, magnet 120, binding post 80, conductor 152, to contact 153, mercury 142, contact 154, conductor 155, to battery 21. In case, however, the speed is above a predetermined amount the mercury will have moved away from the contacts 153 and 154 and thus the magnet 120 would be deenergized with the result previously described.

What is claimed is:

1. A system of train control comprising: traffic rails, a track circuit in said rails responsive to safe and unsafe conditions, means on the train including an electro-responsive device adapted to short-circuit a train axle and its attached wheels and respond to the condition of the circuit in said rails and tending to apply the brakes under unsafe conditions, speed controlled means for causing the operation of the brake applying means under certain speed conditions, and means for preventing the operation of the brake applying means by the speed controlled means when the condition of the track circuit indicates safe traffic conditions.

2. A traffic controlling device comprising: a pair of train-carried current collecting

shoes arranged to make sliding contact for a substantial surface area each with a different one of the traffic rails, a conductor connecting said shoes and having a degree of electrical conductivity relatively higher than that of a train axle, said conductor forming a coil, and an electro-responsive device including said coil as a part thereof, said electro-responsive device operating to indicate the electrical condition of said rails. 70

3. A traffic controlling device comprising: a pair of train-carried current collecting shoes arranged to make sliding contact with the traffic rails, a conductor connecting said shoes and extending across the train closely adjacent the level of said shoes, said conductor forming a coil, and an electro-responsive device including said coil as a part thereof, said electro-responsive device operating to indicate the electrical condition of said rails. 75

4. A traffic controlling device comprising: a pair of train-carried current collecting shoes arranged to make sliding contact for a substantial surface area each with a different one of the traffic rails, a conductor connecting said shoes and having a degree of electrical conductivity relatively higher than that of a train axle and extending across the train closely adjacent the level of said shoes, said conductor forming a coil, and an electro-responsive device including said coil as a part thereof, said electro-responsive device operating to indicate the electrical condition of said rails. 80

5. A traffic controlling device comprising: a pair of train-carried current collecting members arranged to make contact with the traffic rails, a conducting bar extending across the train, conductors connecting the ends of said bar to said members, a portion of said bar having a coil formation, and an electro-responsive device including said coil and operating to indicate the electrical condition of said rails. 90

6. A traffic controlling device comprising: a pair of train-carried current collecting members arranged to make contact with the traffic rails, a bar having a degree of electrical conductivity relatively higher than that of a train axle and extending across the train, conductors connecting the ends of said bar to said members, a portion of said bar having a helical formation of comparatively large cross-section, and an electro-responsive device including said coil and operating to indicate the electrical condition of said rails. 105

7. A traffic controlling device comprising: a pair of train-carried current collecting shoes arranged to make sliding contact for a substantial area of engagement with the traffic rails, a conducting member having a degree of electrical conductivity relatively higher than that of a train axle and extending across the train, conductors connecting the ends of said member to said shoes, a por- 110

tion of said member having a coil formation of strip-shaped turns with a comparatively large cross-section, and an electro-responsive device including said coil and operating to indicate the electrical condition of said rails.

8. A traffic controlling device comprising: a pair of train-carried current collecting shoes arranged to make sliding contact for a substantial area of engagement with the traffic rails, a bar having a degree of electrical conductivity relatively higher than that of a train axle and extending across the train adjacent the level of said shoes, flexible cables also having a higher degree of electrical conductivity than that of a train axle connecting said bar to said shoes, a portion of said bar having a relatively massive coil formation, and an electro-responsive device including said coil and operating to indicate the electrical condition of said rails.

9. A traffic controlling device comprising: a pair of train-carried current collecting shoes arranged to make sliding contact with the traffic rails, an electro-responsive device including an elongated energizing coil formed of a strip-shaped conductor extending transversely of the train adjacent the level of said shoes, and flexible cables connecting each end of the coil with points adjacent the rear and the forward ends of the corresponding shoes, said shoes, said coil and said conducting cables having a substantially higher degree of electrical conductivity than that of a train axle.

10. A traffic controlling device comprising: a pair of train-carried current collecting members arranged to make contact with the traffic rails, and electro-responsive device having a coil formed of a metal strip the adjacent convolutions of which are separated by a substantial air gap, a core of magnetic material in said coil, and conductors connecting the ends of said coil to said shoes.

11. A traffic controlling device comprising: a pair of train-carried current collecting members arranged to make contact with the traffic rails, an electro-responsive device having a cylindrical coil formed by a metal strip having a substantial cross-section, a core of magnetic material in said coil, and conductors connecting the ends of said coil to said current collecting members, said members, said conductors and said coil having a degree of electrical conductivity sufficient to short-circuit the rail-bridging connection formed by a train axle and its attached wheels.

12. A traffic controlling device comprising: a pair of train-carried current collecting shoes arranged to make sliding contact with the traffic rails, devices for causing the movement of the shoes along the rails with the train but permitting vertical movement of the shoes in relation to the train, a conducting member extending transversely of the

train, a portion of said member having a coil formation, a plurality of flexible conductors connecting each end of the conducting member to separated points in the corresponding shoe, and an electro-responsive device including the coil portion of said member and operating to indicate the electrical condition of said traffic rails.

13. In an automatic train control system for protecting railway traffic, in combination: 75 a railway vehicle and a track therefor; permissive speed means on the vehicle adapted to be changed to establish several permissive speed limits for the vehicle; and means comprising elements on the vehicle and along the track arranged in electrical co-operative relation for changing said permissive speed means to a variable degree at control points along the track in accordance with the extent of unoccupied track in advance of the vehicle.

14. In an automatic train control system for protecting railway traffic, in combination: 90 a railroad track provided with normally closed track circuits for detecting the presence of trains at different places along the track; a vehicle and automatic train control apparatus therefor operable under varying influences to automatically enforce correspondingly different limitations on the speed of the vehicle, and means governed by said track circuits for establishing electrical communication with said vehicle and for influencing said train control apparatus to a variable degree in accordance with the number 100 of unoccupied track circuits in advance of the vehicle.

15. In a system for automatically protecting traffic on railroad tracks, the combination with automatic mechanism on a vehicle 105 adapted to assume distinctive conditions to establish any one of a plurality of permissive speeds for the vehicle, said mechanism having a tendency to assume its lowest speed condition, of means comprising elements along the track responsive to the presence of trains thereon and co-operating with elements on the vehicle for varying the condition of said mechanism in opposition to said tendency and substantially in accordance with the extent 110 of unoccupied track in advance of the vehicle.

16. In an automatic train control system, the combination with a vehicle, of a permissive speed device on the vehicle normally tending to assume its lowest speed condition, 120 a circuit and control means on the vehicle responsive to electrical energy of varying characteristics for influencing said permissive speed device to higher speed conditions, and means along the trackway for producing 125 varying characteristics of electrical energy in said circuit of a passing vehicle at control points along the track.

17. In an automatic train control system, the combination with a vehicle, of automatic 130

- train control apparatus therefor adapted to enforce automatically any one of a plurality of continuing limitation on its speed, said apparatus having an automatic tendency to assume its lowest speed condition, impulse receiving means on the vehicle, and means including trackway apparatus and circuits responsive to the presence of a train and co-operating with the impulse receiving means on the vehicle for influencing said train control apparatus away from its lowest speed condition to a variable degree dependent upon the distance between said vehicle and the next train ahead. 5
18. In an automatic train control system for railroads having tracks divided into blocks each provided with a normally closed track circuit, an electrically operable brake control device on a vehicle, a normally closed circuit for energizing said device having a plurality of branches in multiple, speed-responsive means governed in accordance with the actual speed of the vehicle for selectively controlling said multiple branches, permissive speed means for selectively controlling said multiple branches in accordance with the safe permissible speed for the vehicle, said permissive speed means being responsive to predetermined variations in the character of 20 electrical energy supplied thereto, trackway means for normally supplying electrical energy to the permissive speed means on a vehicle during its progress through a block, said trackway means acting to vary the character of said energy to conform with the number of unoccupied blocks in advance of the vehicle. 25
19. In an automatic train control system for railroads divided into blocks each provided with a normally closed track circuit, the combination with automatic train control apparatus on a vehicle including electro-responsive permissive speed means tending to change toward its minimum speed condition, and brake control means for automatically applying the brakes when the actual speed of the vehicle exceeds that prescribed by said permissive speed means, of means partly on the vehicle and partly along the track for normally supplying electrical energy of different characteristics to said permissive speed means varying in accordance with the number of blocks in advance of the vehicle which are unoccupied. 40
20. In combination, a railway vehicle, vehicle controlling means thereon, means for controlling said vehicle controlling means comprising a speed controlled part and a speed limit part, electrical means governed by the polarity of current supplied thereto for controlling said speed limit part on the vehicle; electrical means along the trackway co-operating with said third mentioned means to cause currents of different polarity to be supplied thereto. 45
21. In combination, a railway vehicle, vehicle controlling means thereon, means for controlling said vehicle controlling means comprising a speed controlled part and a speed limit part; electrical means governed by the polarity of current supplied thereto for controlling said speed limit part on the vehicle; electrical means along the trackway co-operating with said third mentioned means to cause currents of different polarity to be supplied thereto and signals on the vehicle indicating the control of said speed limit device effected. 50
22. In an automatic train control system for protecting railway traffic, in combination: a railroad track provided with normally closed track circuits for detecting the presence of trains at different places along the track; a vehicle and automatic train control apparatus therefor operable under varying influences to automatically enforce correspondingly different limitations on the speed of the vehicle, and means substantially continuously governed by said track circuits for establishing, at substantially all points along the track, electrical communication with said vehicle and for substantially continuously influencing said train control apparatus to a variable degree in accordance with the number of unoccupied track circuits in advance of the vehicle. 55
23. A system for automatically protecting traffic on railroad tracks including: a traffic track composed of traffic rails and arranged in blocks, a car traveling on the track, and an automatic device on the car, substantially continuously responsive to variations in the influence of current flowing in the traffic rails of the block through which the car is traveling, to impose, in response to a change in traffic conditions and at substantially any point within a block, that one of a plurality of permissive speeds on the car permissible under the particular conditions. 60
24. A system for automatically protecting traffic on railroad tracks including: a traffic track composed of traffic rails and arranged in blocks, a car traveling on the track, and an in part electro-magnetic automatic device on the car, substantially continuously responsive to variations in the influence of current flowing in the traffic rails of the block through which the car is traveling, to impose, in response to a change in traffic conditions and at substantially any point within a block, that one of a plurality of permissive speeds on the car permissible under the particular conditions. 65
25. A system for automatically protecting traffic on railroad tracks including: a traffic track composed of traffic rails and arranged in blocks, a car traveling on the track, and automatic means on the car, including an actual speed device and a brake setting device, substantially continuously responsive 70

- to variations in the influence of current flowing in the traffic rails of a block through which the car is traveling, to impose, in response to a change in traffic conditions and at substantially any point within a block, that one of a plurality of permissive speeds on the car permissible under the particular conditions.
26. A system for automatically protecting traffic on railroad tracks including: a traffic track composed of traffic rails and arranged in blocks, a car traveling on the track, and automatic means, in part electro-magnetic, on the car, including an actual speed device and a brake setting device, substantially continuously responsive to variations in the influence of current flowing in the traffic rails of a block through which the car is traveling, to impose, in response to a change in traffic conditions and at substantially any point within a block, that one of a plurality of permissive speeds on the car permissible under the particular conditions.
27. A system for automatically protecting traffic on railroad tracks including: a traffic track composed of traffic rails and arranged in blocks, a car traveling on the track, and an automatic device on the car, substantially continuously responsive to variations in the influence of current flowing in the traffic rails of the block through which the car is traveling, to impose, in response to successive adverse changes in traffic conditions and at substantially any point within a block, successively lower permissive speeds on the car.
28. A system for automatically protecting traffic on railroad tracks including: a traffic track composed of traffic rails and arranged in blocks, a car traveling on the track, and an in part electro-magnetic automatic device on the car, substantially continuously responsive to variations in the influence of current flowing in the traffic rails of the block through which the car is traveling, to impose, in response to successive adverse changes in traffic conditions and at substantially any point within a block, successively lower permissive speeds on the car.
29. A system for automatically protecting traffic on railroad tracks including: a traffic track composed of traffic rails and arranged in blocks, a car traveling on the track, and automatic means on the car, including an actual speed device and a brake setting device, substantially continuously responsive to variations in the influence of current flowing in the traffic rails of the block through which the car is traveling, to impose, in response to successive adverse changes in traffic conditions and at substantially any point within a block, successively lower permissive speeds on the car.
30. A system for automatically protecting traffic on railroad tracks including: a traffic track composed of traffic rails and arranged in blocks, a car traveling on the track, and an in part electro-magnetic automatic device on the car, substantially continuously responsive to variations in the influence of current flowing in the traffic rails of the block through which the car is traveling, to impose, in response to successive adverse changes in traffic conditions and at substantially any point within a block, successively lower permissive speeds on the car.
31. A system for automatically protecting traffic on railroad tracks including: a traffic track composed of traffic rails and arranged in blocks, a car traveling on the track, and automatic means on the car, including an actual speed device and a brake setting device, substantially continuously responsive to variations in the influence of current flowing in the traffic rails of the block through which the car is traveling, to determine, in response to favorable or adverse changes in traffic conditions and at substantially any point within a block, that one of a plurality of permissive speeds permissible under the particular conditions.
32. A system for automatically protecting traffic on railroad tracks including; a traffic track composed of traffic rails and arranged in blocks, a car traveling on the track, and automatic means, in part electro-magnetic, on the car, including an actual speed device and a brake setting device, substantially continuously responsive to variations in the influence of current flowing in the traffic rails of the block through which the car is traveling, to determine, in response to favorable or adverse changes in traffic conditions and at substantially any point within a block, that one of a plurality of permissive speeds permissible under the particular conditions.
33. A system for automatically protecting traffic on railroad tracks including: a traffic track composed of traffic rails and arranged in blocks, a car traveling on the track, an automatic device on the car, substantially continuously responsive to variations in the influence of current flowing in the traffic rails of the block through which the car is traveling, to impose, in response to a change in traffic conditions and at substantially any point within a block, that one of a plurality of permissive speeds on the car permissible under the particular conditions, and a track circuit controlling the flow of current in the traffic rails of a block, and substantially continuously responsive to traffic conditions of another block, acting through the medium of the traffic rails to control the automatic device on the car.
34. A system for automatically protecting traffic on railroad tracks including: a traffic track composed of traffic rails and arranged in blocks, a car traveling on the track, an in part electro-magnetic automatic device on the car, substantially continuously responsive to variations in the influence of current flowing in the traffic rails of a block through which the car is traveling, to impose, in response to successive adverse changes in traffic conditions and at substantially any point within a block, successively lower permissive speeds on the car.

41. A system for automatically protecting traffic on railroad tracks including: a traffic track composed of traffic rails and arranged in blocks, a car traveling on the track, automatic means on the car, including an actual speed device and a brake setting device, substantially continuously responsive to variations in the influence of current flowing in the traffic rails of the block through which the car is traveling, to determine, in response to favorable or adverse changes in traffic conditions and at substantially any point within a block, that one of a plurality of permissive speeds permissible under the particular conditions, and a track circuit controlling the flow of current in the traffic rails of a block, and substantially continuously responsive to traffic conditions of another block, acting through the medium of the traffic rails to control the automatic means on the car.
42. A system for automatically protecting traffic on railroad tracks including: a traffic track composed of traffic rails and arranged in blocks, a car traveling on the track, automatic means, in part electro-magnetic, on the car, including an actual speed device and a brake setting device, substantially continuously responsive to variations in the influence of current flowing in the traffic rails of the block through which the car is traveling, to determine, in response to favorable or adverse changes in traffic conditions and at substantially any point within a block, that one of a plurality of permissive speeds permissible under the particular conditions, and a track circuit controlling the flow of current in the traffic rails of a block, and substantially continuously responsive to traffic conditions of another block, acting through the medium of the traffic rails to control the automatic means on the car.
43. A system of train control comprising: traffic rails divided by insulation into conducting blocks, a source of electric energy connecting the rails of each block, a train, electro-responsive train controlling means on said train in shunt with said traffic rails, means for controlling the circuit in one block from another block to apply the brakes on a train traveling in said first-named block, means for automatically releasing the brakes to permit the train to proceed at a predetermined speed, means for controlling the circuit in said train-occupied block from a third block to apply the brakes on said train, and means for automatically releasing the brakes to permit the train to proceed at a different speed.
44. A system of train control comprising: traffic rails, a track circuit in said rails, a vehicle, controlling means on said vehicle constructed and arranged to be placed in shunt with the track circuit and to short-circuit the adjacent wheels and axles, speed controlled means, means for affecting said

circuit to operate said controlling means when the vehicle is traveling at a certain speed, and means cooperating with said speed controlled means for affecting said circuit to operate said controlling means when the vehicle is traveling at a different speed.

45. A system of train control comprising: traffic rails divided by insulation into conducting blocks, a source of electric energy connecting the rails of each block, a resistance also connecting the rails of each block whereby a current of small volume normally flows in said block circuit, a train, electro-responsive train controlling means on said train bridging said traffic rails and having a comparatively low resistance whereby a current of large volume flows through said train controlling means, speed controlled means, and means for controlling the circuit in one block from another block and cooperating with the speed controlled means to reduce the speed of a train traveling in said first-named block.

46. A system of train control comprising: traffic rails divided by insulation into conducting blocks, a source of electric energy connecting the rails of each block, a resistance also connecting the rails of each block whereby a current of small volume normally flows in said block circuit, a train, electro-responsive train controlling means on said train bridging said traffic rails and having a comparatively low resistance whereby a current of large volume flows through said train controlled means, speed controlled means, and means for controlling the circuit in one block from another block cooperating with said speed controlled means to automatically increase the speed of a train traveling in said first-named block.

47. A system of train control comprising: traffic rails divided by insulation into conducting blocks, a source of electric energy connecting the rails of each block, a resistance also connecting the rails of each block whereby a current of small volume normally flows in said block circuit, a train, electro-responsive train controlling means on said train bridging said traffic rails and having a comparatively low resistance whereby a current of large volume flows through said train controlling means, speed controlled means, and means for controlling the circuit in one block from another block cooperating with said speed controlled means to automatically decrease or increase the speed of a train traveling in said first-named block.

48. A system of train control comprising: traffic rails divided by insulation into conducting blocks, a source of electric energy connecting the rails of each block, a train, electro-responsive train controlling means on said train in shunt with said traffic rails, means for controlling the circuit in one block from another block to apply the brakes on

a train traveling in said first-named block, means for automatically releasing the brakes to permit the train to proceed at a predetermined speed, means for controlling the circuit in said train-occupied block from a third block to apply the brakes on said train, and means for automatically releasing the brakes to permit the train to proceed at a different predetermined speed.

49. A system of train control comprising: traffic rails divided by insulation into conducting blocks, a source of electric energy connecting the rails of each block, a resistance also connecting the rails of each block whereby a current of small volume normally flows in said block circuit, a train, electro-responsive train controlling means on said train in shunt with said traffic rails and having a comparatively low resistance whereby a current of large volume flows through said train controlling means, speed controlled means, and means for controlling the circuit in one block from another block cooperating with said speed controlled means to operate said train controlling means when the train is traveling at a certain speed.

50. A system of train control comprising: traffic rails divided by insulation into conducting blocks, a source of electric energy connecting the rails of each block, a train, electro-responsive train controlling means on said train in shunt with said traffic rails, speed controlled means, means for controlling the circuit in one block from another block and cooperating with said speed controlled means to operate said train controlling means when the train is traveling at a certain speed, and means for controlling the circuit in said train-occupied block from a third block and cooperating with said speed controlled means to operate said train controlling means when the train is traveling at a different speed.

51. A system for automatically protecting traffic on railroad tracks including: a traffic track composed of traffic rails and arranged in blocks, a car traveling on the track, track circuit means associated with each block to supply flow of current to the traffic rails of a block, translating means substantially continuously responsive to the influence of current flow in the rails of a block to vary, when a change in traffic conditions of one block occurs, the influence of the track circuit means of another block, and automatic means on the car to impose on the car different speed limits in response to different traffic conditions including a permissive speed device substantially continuously responsive to variations in the influence of current flow in the traffic rails of the block through which the car is traveling, an actual speed device substantially continuously responsive to the speed of the car, and brake setting means substantially continuously responsive to the

joint control of the permissive and actual speed devices.

52. A system for automatically protecting traffic on railroad tracks including: a traffic track composed of traffic rails and arranged in blocks, a car traveling on the track, track circuit means associated with each block to supply flow of current to the traffic rails of a block, translating means substantially continuously responsive to the influence of current flow in the rails of a block to vary, when a change in traffic conditions of one block occurs, the influence of the track circuit means of another block, and automatic means on the car to impose on the car different speed limits in response to different traffic conditions including translating means on the car substantially continuously responsive to variations in the influence of current flow in the traffic rails of the block through which the car is traveling, a permissive speed device substantially continuously responsive to the car carried translating means, an actual speed device substantially continuously responsive to the speed of the car, and brake setting means substantially continuously responsive to the joint control of the permissive and actual speed devices.

53. A system for automatically protecting traffic on railroad tracks including: a traffic track composed of traffic rails and arranged in blocks, a car traveling on the track, a permissive speed device on the car substantially continuously responsive to variations in the influence of current flow in the traffic rails of the block through which the car is traveling to thereby establish different speed control limits, an actual speed device also on the car substantially continuously responsive to the speed of the car to thereby assume different speed control conditions, a brake setting means on the car substantially continuously responsive to the joint control of the permissive and actual speed devices, and a track circuit controlling the flow of current in the traffic rails of a block, and substantially continuously responsive to traffic conditions of another block, acting through the medium of the traffic rails to control the permissive speed device on the car.

54. A system for automatically protecting traffic on railroad tracks including: a traffic track composed of traffic rails and arranged in blocks, a car traveling on the track, a permissive speed device on the car substantially continuously responsive to variations in the influence of current flow in the traffic rails of the block through which the car is traveling to thereby establish different speed control limits, an actual speed device also on the car substantially continuously responsive to the speed of the car to thereby assume different speed control conditions, a brake setting means on the car substantially continuously responsive to the joint control of the per-

- missive and actual speed devices, track circuit means associated with each block to supply flow of current to the traffic rails of a block, and translating means substantially continuously responsive to the influence of current flow in the traffic rails of a block to vary, when a change in traffic conditions of one block occurs, the influence of the track circuit means of another block.
55. A system for automatically protecting traffic on railroad tracks including: a traffic track composed of traffic rails and arranged in blocks, a car traveling on the track, track circuit means associated with each block to supply flow of current to the traffic rails of a block, translating means substantially continuously responsive to the influence of current flow in the rails of a block to vary, when a change in traffic conditions of one block occurs, the influence of the track circuit means of another block, translating means on the car substantially continuously responsive to variations in the influence of current flow in the traffic rails of the block through which the car is traveling, a permissive speed device substantially continuously responsive to the car carried translating means to thereby establish different speed control limits, an actual speed device also on the car substantially continuously responsive to the speed of the car to thereby assume different speed control conditions, and a brake setting means on the car substantially continuously responsive to the joint control of the permissive and actual speed devices.
56. A system for automatically protecting traffic on railroad tracks including: a traffic track composed of traffic rails and arranged in blocks, a track circuit completed through the traffic rails of a block and responsive to traffic conditions for supplying across the traffic rails at the exit end of the block a car governing current, a car traveling on the track, automatic means on the car, substantially continuously responsive to variations in the influence of the car governing current flowing in the traffic rails of the block through which the car is traveling, including: a signaling device and a brake-setting device, and means on the car to annul the influence exercised over the brake-setting device without annulling the influence exercised over the signaling device.
57. A system for automatically protecting traffic on railroad tracks including: a traffic track composed of traffic rails and arranged in blocks, a track circuit completed through the traffic rails of a block and responsive to traffic conditions for supplying across the traffic rails at the exit end of the block a car governing current, a car traveling on the track, automatic means on the car, substantially continuously responsive to variations in the influence of the car governing current flowing in the traffic rails of the block through which the car is traveling, including: a signaling device and a brake-setting device, and means on the car to annul the influence exercised over the brake-setting device without annulling the influence exercised over the signaling device.
58. A system for automatically protecting traffic on railroad tracks including: a traffic track composed of traffic rails and arranged in blocks, a track circuit completed through the traffic rails of a block and responsive to traffic conditions for supplying across the traffic rails at the exit end of the block a car governing current, a car traveling on the track, automatic means on the car, substantially continuously responsive to variations in the influence of the car governing current flowing in the traffic rails of the block through which the car is traveling, including: a signaling device and a brake-setting device, and an actual speed device on the car to annul the influence exercised over the brake-setting device without annulling the influence exercised over the signaling device.
59. A system for automatically protecting traffic on railroad tracks including: a traffic track composed of traffic rails and arranged in blocks, a track circuit completed through the traffic rails of a block and responsive to traffic conditions for supplying across the traffic rails at the exit end of the block a car governing current, a car traveling on the track, automatic means on the car, substantially continuously responsive to variations in the influence of the car governing current flowing in the traffic rails of the block through which the car is traveling, including: a signaling device and a brake-setting device, and an actual speed device on the car to annul, under adverse traffic conditions, the influence exercised over the brake-setting device without annulling the influence exercised over the signaling device.
60. A system for automatically protecting traffic on railroad tracks including: a traffic track composed of traffic rails and arranged in blocks, a track circuit for each block including the traffic rails of the block and one current source, a second track circuit for each block including the traffic rails of the block and a second current source to be connected across the traffic rails at the exit end of the block, means controlled by the first track circuit to connect the second source of another block to the rails of said other block, traffic controlled means to reverse the connections between said second source and the rails, a car traveling on the track, and car carried apparatus continuously responsive to variations in the influence of current from the second source flowing in the rails of the block through which the car is traveling.
61. A system for automatically protecting traffic on railroad tracks including: a traf-

fic track composed of traffic rails and arranged in blocks, trackway circuit means for each block including a trackway source of current to be connected across the traffic rails at the exit end of a block, a car traveling on the track, automatic means, including a brake-setting device, on the car substantially continuously responsive to the influence of the trackway circuit means to apply the brakes under adverse traffic conditions, and an actual speed device on the car to permit the latter to proceed at a predetermined speed under adverse traffic conditions.

62. A system for automatically protecting traffic on railroad tracks including: a traffic track composed of rails and arranged in zones of influence, a trackway source of current connected across said rails, trackway means responsive to traffic conditions to reverse the connection between a trackway source and the rails for a portion of a zone and for cutting off connection between said source and rails for the remaining portion of the zone, a car to travel on the track, and car-carried apparatus responsive to variations of influence of the current source and to give a caution indication when reverse connections are established and a danger indication when current is cut off between the trackway source and the rails.

63. A train control system including: traffic rails arranged in blocks, two trackway sources of current for each block, each of said sources bridged across the traffic rails of a block, one of said sources supplying a train governing current and the other source supplying a control current to the traffic rails in series, circuit means responsive to the control current flowing in the rails of a block to control the supply of train governing current to the traffic rails of another block, a train, and automatic means on the train substantially continuously responsive to the influence of the train governing current flowing in the traffic rails of a block being traversed by a train but not effectively responsive to the control current flowing in the traffic rails of said block.

64. A system for protecting traffic on railroad tracks including: a traffic track composed of rails arranged in blocks, trackway means to supply across the rails at the exit end of a block a clear or a caution train governing current, a train, a train-carried control relay continuously responsive to the influence of either train-governing current flowing in the rails of the block through which the train is traveling, two train-carried repeater relays so arranged that when either of said repeater relays is energized the other is not, one repeater relay energized only when the control relay is influenced by clear train-governing current, the second repeater relay energized only when the control relay is influenced by caution train-governing current,

and train-carried signaling means controlled to give a clear or a caution indication depending upon which repeater relay is energized.

65. A system for protecting traffic on railroad tracks including: a traffic track composed of rails arranged in blocks, a trackway source of clear and caution train-governing current capable of being selectively connected across the traffic rails at the exit end of the block, in accordance with traffic conditions ahead, a train, a train-carried control relay continuously and selectively responsive to the influence of the clear or caution train-governing current flowing in the rails of the block through which the train is traveling, two train-carried repeater relays so arranged that when either of said repeater relays is energized the other is not and selectively energized when the control relay is influenced by either clear or caution train-governing track current, and clear, caution and danger train-carried signaling circuits selectively controlled by the two repeater relays.

66. A system for protecting traffic on railroad tracks including: a traffic track arranged in blocks, a trackway source of clear and caution train-governing current capable of being selectively connected to the traffic track in accordance with traffic conditions ahead, a train, a train-carried control relay continuously and selectively responsive to the influence of clear or caution train-governing current in the track of the block through which the train is traveling, two train-carried repeater relays so arranged that when either of said repeater relays is energized the other is not and selectively energized when the control relay is influenced by either clear or caution train-governing current, and clear, caution and danger train-carried cab signaling circuits selectively controlled by the two repeater relays.

67. A train control system including: traffic rails arranged in blocks, two trackway sources of current for each block, each of said sources bridged across the traffic rails of a block, one of said sources supplying a train governing current and the other source supplying a control current to the traffic rails in series, circuit means responsive to the control current flowing in the rails of a block to control the supply of train governing current to the traffic rails of another block, a train, and automatic means on the train substantially continuously responsive to the influence of the train governing current flowing in the traffic rails of a block being traversed by a train but not effectively responsive to the control current flowing in the traffic rails of said block.

68. In a system for automatically protecting traffic on railroad tracks, the combination with automatic mechanism on a vehicle for retarding the movement thereof, of a normally closed circuit for governing said mecha-

nism, a permissive speed device having a tendency to assume its lowest speed condition, means controlled by said device for opening said circuit when the actual speed of the vehicle exceeds the permissive speed prescribed by said device, and normally acting impulse transmitting means comprising trackway elements cooperating with the element on the vehicle for influencing said device from its lowest speed condition to a variable extent in accordance with the extent of unoccupied track in advance of the vehicle.

69. In a system for automatically protecting traffic on railroad tracks, the combination with automatic apparatus on a vehicle adapted to restrict the speed thereof to any one of a plurality of speeds, said apparatus having a tendency to impose the lowest speed restriction, of traffic controlled means acting 15 in opposition to said tendency to govern said apparatus substantially in accordance with the space between said vehicle and another train ahead.

70. In a system for automatically protecting traffic on railroad tracks, the combination with automatic mechanism for controlling the movement of a vehicle comprising speed responsive means having its controlling condition governed by the actual speed of the 20 vehicle, of a permissive speed means capable of having its controlling condition regulated by the varying polarity of electrical energy supplied thereto, and means governed jointly by said speed responsive means and said permissive speed means for retarding the movement of the vehicle whenever the actual speed exceeds the prescribed permissive speed.

71. In a system for automatically protecting traffic on railroad tracks, the combination with automatic mechanism for controlling the movement of a vehicle comprising speed responsive means having its controlling condition governed by the actual speed of the vehicle, of a permissive speed means capable 45 of having its controlling condition regulated by the varying polarity of electrical energy supplied thereto, and means governed jointly by said speed responsive means and said permissive speed means for retarding the movement of the vehicle whenever the actual speed exceeds the prescribed permissive speed and signals on the vehicle operated to show the regulation of the controlling condition of the permissive speed means effected.

72. A train carried system including: train controlling means, electroresponsive means which, when energized, holds the train controlling means inoperative, speed control means for rupturing a circuit through said 50 electroresponsive means when the train is running above a certain speed, a second speed control means for rupturing a circuit through said electroresponsive means when the train is running above a certain lesser speed, and means for rupturing the connection through

said first mentioned speed control means regardless of the speed of the train under certain traffic conditions.

73. A train carried system including: train controlling means, electroresponsive means which, when energized, holds the train controlling means inoperative, speed control means for rupturing a circuit through said electroresponsive means when the train is running above a certain speed, a second speed 75 control means for rupturing a circuit through said electroresponsive means when the train is running above a certain lesser speed, means for rupturing the connection through said first mentioned speed control means regardless of the speed of the train under certain traffic conditions, and means for automatically completing a circuit through said electroresponsive means independently of the two speed control means under certain other traffic conditions.

74. A train carried system including: train controlling means, electroresponsive means which, when energized, holds the train controlling means inoperative, a circuit normally completed through said electroresponsive means under safety conditions, means acting under caution conditions for rupturing said circuit and establishing a speed control circuit through the electroresponsive means said circuit to be automatically ruptured when the train exceeds a certain speed, means for rupturing said second circuit under danger conditions, and a circuit including a speed control means through said electroresponsive 100 device to permit the train to proceed at a minimum speed under danger conditions.

Signed at New York city in the county of New York and State of New York this 16th day of October A. D. 1914.
